UNITED STATES PATENT OFFICE

ADOLPH ROTH, OF NEW YORK, N. Y.

COMBINED LEASH AND WHIP.

Application filed August 2, 1923. Serial No. 655,315.

To all whom it may concern:

Be it known that I, ADOLPH ROTH, a citizen of the United States, and a resident of the city of New York, borough of Manhattan, in the county and State of New York, have invented a new and improved Combined Leash and Whip, of which the following is a full, clear, and exact description.

10 The present invention relates to new and useful improvements in restraining devices, and it pertains more particularly to a combined whip and leash for animals, such as dogs, and the like.

15 It is one of the primary objects in the invention to provide an article of the above type which may be used either as a leash or a whip.

It is a further object of the invention to 20 construct the body portion of the device in such a manner that it will have sufficient rigidity when used as a whip and yet such rigidity of the body portion will not interfere with the successful use of the device 25 as a leash.

It is a further object of the invention to construct the device in such a manner that a loop is formed at one end to provide a handle which also may be reduced in size for 30 the purpose of securing it to a projection, such as a door knob, hook, or the like.

With the above and other objects in view, reference is had to the accompanying drawings, in which

35 Figure 1 is a view in side elevation of an article constructed in accordance with the present invention;

Fig. 2 is a transverse sectional view taken on the line 2-2 of Fig. 1.

40 Referring more particularly to the drawings, the device comprises a stiffened body portion 5. In forming the device a strap of leather or other suitable material is provided on one of its ends with a loop 6, which

45 loop is formed by folding the end backwardly over the body portion. This loop is adapted to carry a swivel 7, and connected to the swivel 7, by means of an eye 8, is a catch or clip 9, which latter is of the usual

50 construction employed in restraining devices. The strap is then folded intermediate of its ends, as designated by the reference character 10, and the portion 11 thereof is laid parallel to and in contact with the other

55 member 12 of the strap.

Between the two members 11 and 12 is

placed a stiffening element 13, preferably formed of metal, such metal possessing a certain amount of resiliency in order to give body to the two members 11 and 12. As indicated by the reference character 13, these two members 11 and 12 are stitched together throughout the length of the stiffening member 13, thus forming a relatively rigid body portion between the ends of 65 the device.

By such a construction, a loop is formed on one end of the leash, said loop being designated by the reference character A, and for the purpose of contracting the loop, a 70 sliding member 15 is employed, which sliding member is preferably formed from the same material as the leash.

In stitching the members 11 and 12 together, the member 11 is skived, as shown 75 at 16, and the looped end 6 of the member 12 is also skived. The skived portions of these extremities are then overlapped and are secured together by the stitching 14 heretofore mentioned, thus giving the leash a 80 finished appearance.

When the device is used as a leash, the catch 9 is engaged with a ring or the like in the collar worn by the animal, and the loop A is used as the hand-grip of the 85 device.

When, however, the device is used as a whip, the end carrying the clip or catch 9 is gripped by the hand and the looped portion A is used as the whip.

When it is desired to secure an animal in a fixed position, such, for example, as to a fence, door, or the like, the loop portion A is engaged with a suitable projection and the sliding element 15 is moved along the 95 device until the loop A is contracted about the projection, thus retaining the animal and securing the device against accidental displacement.

From the foregoing it is apparent that the 100 present invention provides a restraining device which may be used either as hand leash or whip, or the device may further be used as means for leashing an animal in a given place.

105 What is claimed is:

1. A device of the character described comprising a length of material having a loop formed on one of its ends, the other end of said material being bent backwardly 110 upon itself to form a looped portion, said second mentioned end being secured to the

first-mentioned end by stitching, a stiffening element interposed between said overlapped ends, and attaching means carried by said first-mentioned looped end.

5. 2. A leash comprising a strip of leather or the like having a loop formed on one of its ends, an attaching clip secured in said loop, the other end of said strip of material being bent backwardly upon the body portion to provide a looped end, said second-mentioned loop being stitched to the first-mentioned loop to provide a body portion, and a metal strap mounted in the body portion of the leash.

3. A leash formed from a single strap, 15 said strap having a loop formed on one end a retaining clip carried by said loop, the other end of said strap being bent backwardly upon itself to provide a hand grip in the form of a loop, stitching for securing 20 said second end to the first-mentioned end and to the portion which it overlies, and a metal strap interposed between said overlapping members, said metal strap serving to lend rigidity to the body portion of the 25 leash.

ADOLPH ROTH.
